UNITED STATES PATENT OFFICE.

SYLVESTER BYRNE, OF PHILADELPHIA, PENNSYLVANIA.

KNIFE-POLISHING MACHINE.

SPECIFICATION forming part of Letters Patent No. 351,738, dated November 2, 1886.

Application filed September 3, 1885. Serial No. 176,048. (No model.)

To all whom it may concern:

Be it known that I, SYLVESTER BYRNE, a citizen of the United States, residing at Philadelphia, in the county of Philadelphia and State of Pennsylvania, have invented certain new and useful Improvements in Knife-Polishing Machines, of which the following is a specification, reference being had therein to the accompanying drawings.

10 My invention relates to improvements in knife-blade-polishing machines, in which two disk-plates revolve in directly opposite directions; and the objects of my improvements are, first, to secure an increased rotary motion by having the disk which accomplishes the polishing operation of the blade to move in a distinct and opposite rotary direction from the disk-plate, in which the handles of the knives are secured; second, to afford means 15 for polishing more than one knife-blade at a single operation; and, third, to afford facilities for the proper adjustment of the knife-blades to the polishing surface, that each may receive a uniform polish. I attain these objects by the mechanism illustrated in the accompanying drawings, in which—

Figure 1 is a side elevation of the entire machine. Fig. 2 is a vertical section on line x x of Fig. 1. Fig. 3 is a top view of the revolving plates. Fig. 4 is a top face view of the revolving carrier-plate having its cap removed. Fig. 5 is a top plan view of a portion of the outer revolving plate, showing its interior construction.

35 Similar letters refer to similar parts throughout the several views.

In the drawings, A represents the frame-work of the machine centrally located, in which is a vertical sleeve, N, secured at its top above the frame-work to a circular plate, F. Passing entirely through said sleeve N is a shaft, E, which has secured near its top and within the body of the circular plate F a circular carrier-plate, C, having a cap-plate, 40 e. A horizontal shaft, M, having a fly-wheel, s, at one end outside of the frame-work A, while its inner end is provided with a bevel-gear, G, which meshes with smaller bevel-gears, H and D, is mounted on the frame-work A. 45 The one marked D is secured to the sleeve N, and the one marked H is secured to the shaft E. Said horizontal shaft M is constructed with a crank, m, to which the treadle o is connected by means of the connecting-rod n.

The vertical shaft E is screw-threaded, as at 55 e, for a short distance at its top, to receive the nut k, for holding the cap-plate e.

The carrier-plate C is constructed in the tangential grooves e', to receive the handles of the knives, and adjustable springs b, arranged in connection with each knife, serve to keep the blades of the same firmly down upon the polishing-surface.

When operating the machine, the handle to each knife is slipped into its proper groove, 65 e', in the carrier-plate C, and its associate spring, b, is drawn out from under the cap-plate C and rests in its proper position upon the knife-blade, when the cap-plate is forced firmly down upon the handles of the knives and 70 springs b by means of the thumb-nut k. Motion now being imparted to the horizontal crank-shaft M by means of the treadle o and connecting-rod n. The bevel-gears D and H, respectively, will impart a rotary motion to 75 the sleeve N and shaft E, but in a directly opposite direction, the result will be that a single revolution of the plate F will be met with a complete opposite revolution of the carrier-plate C, resulting in a high velocity of the 80 friction-plate over the knife. Said frictional plate is constructed with a flange, f, which serves to keep the brick-dust, emery, or similar material used for polishing from being thrown off by the centrifugal force. 85

By the use of a machine such as I have described a number of knife-blades can be polished at a single operation and much quicker than by handling singly in the usual manner, while the uniform position which each occupies in relation to the frictional surface and manner of holding them recommends it as a thoroughly practical and efficient machine, inasmuch as each blade will receive the same polish. 90

Having thus described my invention, I 95 claim—

The combination, in a knife-polishing machine, of the carrier-plate C, having tangential grooves e', springs b, cap-plate e, thumb-nut k, and vertical shaft E, substantially as set forth.

In testimony whereof I affix my signature in presence of two witnesses.

SYLVESTER BYRNE.
